UNITED STATES PATENT OFFICE.

WILLIAM G. SHEDD, OF LEADVILLE, COLORADO.

SASH-CORD GUIDE.

SPECIFICATION forming part of Letters Patent No. 410,741, dated September 10, 1889.

Application filed January 28, 1889. Serial No. 297,754. (No model.)

To all whom it may concern:

Be it known that I, WILLIAM G. SHEDD, a citizen of the United States, residing at Leadville, in the county of Lake and State of Colorado, have invented a certain new and useful Improvement in Cases for Sash-Pulleys, of which the following is a specification, reference being had to the accompanying drawings.

10 My invention relates to cases for sash-pulleys, and is designed to simplify and cheapen the manufacture of such cases and to produce a durable sash-pulley case of sheet metal.

15 My invention consists in the construction and arrangement of the case for sash-pulleys described in this specification, and more particularly pointed out in the claims.

20 In the drawings, Figure 1 is a perspective view of my case inclosing a pulley-wheel. Fig. 2 shows a side elevation of the same with a portion of one wing cut away. Fig. 3 is an end elevation of the same. Fig. 4 represents the form of blank for my case as stamped from sheet metal, the dotted straight lines 25 showing where the blank is folded or bent over in forming the case; and Fig. 5 represents an area of sheet metal, showing in broken lines a series of hexagonal figures, on one of which Fig. 4 is outlined without repeating the letters of reference, thus illustrating the manner in which the blanks represented by Fig. 4 can be cut. A modified but less desirable form of blank is also outlined on another of the hexagonal figures 30 shown in Fig. 5, also without letters of reference, as such modified form of blank is so nearly similar to that shown in Fig. 4 as to be readily understood by the letters of reference shown on Fig. 4.

35 40 The general outline of the blank from which the pulley-case is formed is that of a flattened hexagon, and, as shown by the broken lines in Fig. 5, such blanks can be cut with little or no waste between the blanks 45 from a sheet-metal plate. The triangular pieces α in Fig. 5 are, however, preferably cut away from the form of blank illustrated by Fig. 4, to admit of making a broader surface on the face of the eyelets A^2 , to allow an easier 50 insertion of the case in the frame in which the sash moves, and to give a neater appear-

ance to the case than would be possible were such triangular pieces not removed.

The blank consists, essentially, of the wings A, having slots a^2 and journal-bearings a^4 , 55 and the face areas A' , terminating in the eyelets A^2 , which eyelets should be finished with bevel-sockets, in which to insert ordinary screws in securing the case to the frame inclosing the sash, and the T parting-strips a , 60 with extensions a^3 , cut from the recesses a' , as shown in the drawings. To insure a neat joint in folding over, especially where the case is made from heavy sheet metal, the wings A should preferably be slightly cut, as 65 shown at the points marked a^5 . The blank thus stamped, pressed, or struck out is bent on the dotted straight lines shown in Fig. 4 into the form shown in Fig. 1. The two wings A of the folded blank support the 70 pulley-wheel B in the bearings a^4 , and the T-strips a being bent down form parting-strips, their extensions a^3 being inserted in the slots a^2 , such parting-strips to be preferably bent back at points marked a^6 and slightly curved, 75 as shown in Figs. 1 and 2, to admit of the case for a given diameter of pulley-wheel being made from a smaller piece of sheet metal, and through a shorter opening in its face, in which the pulley-wheel revolves, to allow of a 80 greater length in the turned-down areas a^7 , to give proper strength to the case, and at the same time give a proper clearance to the sash cord, chain, or tape than would be possible were the parting-strips a bent down perpendicular to the face areas A' without being slightly curved.

If desired, the extensions a^3 may be riveted down to prevent the wings A from spreading, though I do not consider it necessary to do 90 so, especially as by making a close or tight fit the extensions a^3 will be quite firmly held by the slots a^2 without riveting. In fact, the extensions a^3 and the slots a^2 may be omitted; but I prefer to use them, especially as they 95 help to stiffen the case through one part supporting another part, particularly if the extensions a^3 are riveted down.

The sash-pulley case, as illustrated in Figs. 1, 2, and 3, is represented as inclosing a 100 grooved pulley-wheel B, with solid hub or axis projecting through the journal-bearings

- a^4 . Such journal-bearings may be made broader than the thickness of the sheet metal in the case by making the perforations smaller and turning down a narrow rim, as indicated 5 by dotted circles at a^8 , either without cutting the metal in such rim or after making a series of cuts in it, as shown at a^9 ; and in case the metal is so turned down at the journal-bearings it should be turned down so as to 10 project toward the inside of the case, so that the projections may not interfere with neatly inserting the sash-pulley complete in a mortise with straight sides in the frame inclosing the sash.
- 15 Should it be deemed best, the pulley-wheel can be mounted to run loose on an axle riveted in place in the wings of the case through suitable perforations therein in lieu of the journal-bearings at the points marked a^4 in 20 the drawings.

The pulley-wheel for my sash-pulley case can of course be made at the rim with a groove for a cord, with projections to engage with or in the links of a chain, or flat to receive a 25 metallic tape wound upon it or to conduct a metallic tape passing over it.

The eyelets of my sash-pulley case should preferably be made so that their outer edges on the sides will be flush with the outside 30 surface of the wings after such wings are bent down in place against the edges of the parting-strips, as by such construction of the eyelets at their outer edges they can be neatly countersunk in the frame in which the sash 35 moves through the use of the same bit or auger used in making the mortise for the main body of the sash-pulley complete.

On account of the small area exposed to

view in the upper surface of the eyelets and of the adjoining face areas along with the 40 upper edges of the wings when the wings are bent down in my sash-pulley case when seated in place, such exposed area can be very cheaply polished or plated, if desired. The shortened opening in the face of the case, 45 through which the pulley-wheel projects, also adds to its neat appearance.

The advantages of my sash-pulley case are obvious, giving economy in the use of materials and combining strength and rigidity 50 with lightness, and being quickly stamped, pressed, or struck from sheet metal, and easily formed, they should be much more cheaply made than the almost exclusively used cast-metal sash-pulley cases, as the latter, to have 55 requisite strength, coupled with the difficulty of making light castings, are necessarily considerably heavier, and the cost of such small castings is considerably more than the cost of sheet metal.

Having fully described my invention, what I claim as new, and desire to secure by Letters Patent, is—

A case for sash-pulleys stamped, pressed, or struck from sheet metal and having wings 65 provided with bearings for the pulley-wheel axis, or perforations in which to rivet the pulley-wheel axle, slots, and parting-strips having extensions which enter the slots in the wings, and face areas terminating in eyelets for securing the case to the frame in which the sash moves, substantially as shown.

WILLIAM G. SHEDD.
